UNITED STATES PATENT OFFICE.

EDWARD RAY INMAN, JR., OF CHICAGO, ILLINOIS, ASSIGNOR TO THE PRAIRIE FARMER PUBLISHING CO., OF CHICAGO, ILLINOIS.

DESIGN FOR A WATCH FOB.

Application filed August 6, 1928. Serial No. 27,730. Term of patent 14 years.

To all whom it may concern:

Be it known that I, EDWARD RAY INMAN, Jr., a citizen of the United States, residing at Chicago, in the county of Cook and State of Illinois, have invented a new, original, and ornamental Design for a Watch Fob, of which the following is a specification, reference being had to the accompanying drawings, forming part thereof.

I claim:

The ornamental design for a watch fob, as shown.

EDWARD RAY INMAN, JR.
